Primary Examiner—Charles A. Rademaker

[57] CLAIM

The ornamental design for a puzzle or similar article, as shown and described.

DESCRIPTION

FIG. 1 is a top plan view of a puzzle or similar article showing my new design;

FIG. 2 is a side elevational view thereof, the other side elevational views being substantially identical.

The bottom of the design is substantially flat, plain and unornamented.

FIG. 1

FIG. 2
